UNITED STATES PATENT OFFICE.

OLIVE E. CLITHERO, OF JANEVILLE, WISCONSIN.

STOVE TRAY ATTACHMENT.

Application filed October 20, 1926. Serial No. 143,003.

This invention relates to a stove tray attachment.

Objects of this invention are to provide a stove tray attachment which is particularly adapted to hold the usual utensils used about a cooking stove, such as spoons, for example, and which is so constructed that it may be detachably applied to the conventional type of stove top so that it may be easily held rigidly and detachably in an accessible position.

Further objects are to provide a very simple device which may be cheaply constructed from standard stock and which may, therefore, be dispensed at a very small cost.

An embodiment of the invention is shown in the accompanying drawings in which:—

Figure 1 is a side elevation of the device showing the adjacent portion of the stove in section;

Figure 2 is a fragmentary plan view of the structure shown in Figure 1.

Referring to the drawings, it will be seen that the device comprises a tray 1, preferably stamped from sheet metal and of elongated formation. As shown in Figure 2, this tray may be conveniently formed with rounded ends and as is apparent from Figures 1 and 2, it is preferably formed with upturned, rounded, marginal flanges. This tray is supported by a transversely extending bar 2, spot welded, or otherwise secured to its underside. This bar extends upwardly at an angle to provide the upwardly projecting arm 3, such arm being preferably provided with a reversely turned end 4 to provide a thickened terminal portion. Through this thickened terminal portion a thumb screw 5 is passed. Preferably, this thumb screw is provided with a pointed end 6.

A spaced arm or bar 7 is secured to the arm or bar 3 so that they may receive be-

tween them the downturned slanting flange 8 of a conventional gas range top 9.

In using the device, it is merely necessary to slip it into place with the flange 8 positioned between the arms 3 and 7. Thereafter, the thumb screw 5 is tightened and the device is rigidly clamped in place.

The device furnishes a very serviceable and accessible support for spoons or other utensils used in cooking, and supplies a need which has been felt for a long time, but which has not been answered. Obviously, the device may be very quickly removed if it is desirable as, for example, for cleaning or for repositioning.

It is apparent that the device may be made with the utmost cheapness and, consequently, may be dispensed at a very small figure.

Although the invention has been described in considerable detail, such description is intended as illustrative rather than limiting as the invention may be variously embodied and as the scope of such invention is to be determined as claimed.

I claim:

A supporting tray for stoves having a downwardly extending flange, said supporting tray comprising a shallow receptacle, a bar extending outwardly therefrom and having an upturned portion provided with a folded upper end, a second bar secured to said first mentioned bar and spaced from the folded upper end, the folded upper end and the spaced portion of the second bar being adapted to receive the flange of a stove between them, said folded upper end having a threaded aperture therethrough, and a pointed wing screw threaded through said aperture and adapted to engage the flange.

In testimony that I claim the foregoing I have hereunto set my hand at Janesville, in the county of Rock and State of Wisconsin.

OLIVE E. CLITHERO.
